UNITED STATES PATENT OFFICE.

EDWARD B. LORENZEN AND CHARLES LORENZEN, OF LORAIN, OHIO.

VALVE.

1,274,297.

Specification of Letters Patent. Patented July 30, 1918.

Application filed November 14, 1916. Serial No. 131,298.

To all whom it may concern:

Be it known that we, EDWARD B. LORENZEN and CHARLES LORENZEN, citizens of the United States, residing at Lorain, in the 5 county of Lorain and State of Ohio, have invented new and useful Improvements in Valves, of which the following is a specification.

This invention relates to certain improvements in valves of the reciprocating type, 10 and aims to provide a valve of this character wherein the use of packing is eliminated, and at the same time leakage effectually prevented.

15 The nature and advantages of the invention will be better understood when the following detail description is read in connection with the preferred form of the invention herein illustrated, the invention residing 20 in the construction, combination and arrangement of parts as claimed.

In the drawing forming part of this specification like numerals of reference indicate similar parts in the several views and 25 wherein:—

Figure 1 is a vertical sectional view taken through a valve constructed in accordance with our invention.

Fig. 2 is a view partly in section taken on 30 line *a—a* of Fig. 1.

Fig. 3 is a horizontal sectional view taken on line *b—b* of Fig. 2.

A valve constructed in accordance with our invention embodies a casing 10 which as 35 shown is of usual design, but which may vary in this respect if so desired. The casing is provided with an inlet port 11, and an outlet port 12, the respective ports being interiorly threaded as shown. The upper 40 end of the casing is open and interiorly threaded to accommodate the main body portion 13 of a bonnet, which main body portion is threadedly associated with the casing in the manner illustrated. The bon-

net 45 includes a centrally disposed tubular member 14 provided with an interiorly extending flange 15 arranged at an appropriate point in its length. The tubular member 14 has positioned therein below the shoulder 15, a sleeve 16, which is carried by a threaded valve stem 17 which projects through the tubular member from a point above the shoulder 15 throughout the adjacent end of said member, the stem being held 50 in position by means of lock nuts 18 threadedly upon the stem and resting upon the upper

extremity of the tubular member 14. The sleeve 16 is mounted for rotation within the tubular member, and such movement is imparted thereto through the instrumental- 60 ity of the wheel or manipulating handle 20 secured upon the stem 17. The sleeve 16 is interiorly threaded for a portion of its length as at 21 to adjustably receive the threaded stem 22 of a disk valve 23 which 65 latter normally engages its seat 24. Manifestly by reason of this construction and arrangement of parts, the valve 23 is moved toward or away from its seat as the occasion may require, by rotating the stem 17 in 70 either one or the other direction, which causes the stem 22 to move in a proper direction within the sleeve 16.

With a view of eliminating the packing that is generally employed with valves of 75 this type, and at the same time effectually prevent leakage, we taper the interior wall of the tubular member 14 an appropriate distance, and correspondingly taper the exterior wall of the sleeve 16 to provide for 80 the proper fit between these parts when the latter are operatively associated. Encircling the stem 17 is a coil spring 26 having one end bearing against the shoulder 15 and its opposite end bearing against the adjacent 85 lock nut 18, the spring possessing the requisite strength to accomplish its function of holding the sleeve 16 in effective engagement with the tapered wall of the tubular member, and thus obviating longitudinal 90 movement of the sleeve within the tubular member under all and any conditions. This fact facilitates the opening and closing of the valve, and renders the structure in its entirety positive in its operation. It will be 95 noted that the tubular member 16 has its end adjacent the shoulder 15 spaced an appreciable distance from the latter to permit the member 16 to be adjusted from time to time to compensate for wear, which necessarily 100 takes place between the tubular member 16 at its point of contact with the portion 13 of the bonnet. For the purpose of carrying this idea into effect we arrange the tubular member 16 in the manner so that the tapered 105 portion thereof projects a considerable distance beyond the lower extremity of the bonnet. Manifestly, as wear takes place between the tubular member 16 and the portion 13 of the bonnet, the nuts 18 can be 110 adjusted upon the stem to bring the tubular member 16 closer to the flange 15, during

which operation the tapered portion of the tubular member 16 is again brought into contact with the body portion 13 of the bonnet, to provide a fluid-tight joint between 5 said parts.

At diametrically opposite points, the casting 10 is provided with ribs 27, which are received between spaced lugs 28 formed on the valve, for the purpose of guiding the 10 valve in its movements toward and away from its seat, and preventing any possibility of the valve rotating during its adjustments. The valve in its entirety is extremely simple 15 in construction, and the arrangement is such that the component parts can be readily and easily disassembled when desired for the purpose of cleaning or repairing such parts.

While it is believed that from the foregoing description the nature and advantages 20 of the invention will be readily apparent without requiring a more extended explanation, we desire to have it understood that what is herein shown is merely illustrative of the preferred embodiment of the invention to which we do not limit ourselves and 25 that such changes may be resorted to when desired as fall within the scope of what is claimed.

What is claimed is:—

30 A valve comprising a casing having an inlet and an outlet, a valve seat, a bonnet detachably secured to the casing and includ-

ing a tubular member beveled at its inner end, an internal annular flange formed on said member at a point in its length, a valve, 35 a threaded stem projecting therefrom, a sleeve rotatably mounted within said tubular member and threadedly associated with said stem, said sleeve being of uniform diameter for a portion of its length, the remaining 40 portion of said sleeve being flared and projecting a considerable distance beyond inner beveled end of said tubular member, said beveled end and flared portion of the sleeve coöperating to provide a fluid-tight joint 45 between the parts, said sleeve being spaced from said flange, a stem projecting from said sleeve through said annular flange and having a threaded portion, nuts adjustably associated with said threaded portion of the 50 stem and with the bonnet, whereby said sleeve may be moved closer to said flange to compensate for wear between the flared portion of said sleeve and the adjacent extremity of said tubular member, and a 55 spring encircling said stem and bearing against said flange and nuts to hold said sleeve against longitudinal movement within the tubular member.

In testimony whereof we affix our signatures.

EDWARD B. LORENZEN.
CHARLES LORENZEN.
